SLIDER FOR SEPARABLE FASTENERS

Gilman M. Gay, Cheshire, Conn., assignor to
 United States Rubber Company, New York,
 N. Y., a corporation of New Jersey

Application December 12, 1939, Serial No. 308,755

3 Claims. (Cl. 24—205.5)

This invention relates to separable slide fasteners and particularly to an improved slider provided with a locking device to prevent the movement of the slider in the direction to separate the fastener elements, the locking device being controlled by a pull member cooperating therewith.

Separable fasteners are used on wearing apparel and it is very desirable to provide a fastener which is small and which will prevent the elements from being separated unintentionally and allow the garment to open up. For the purpose of providing the foregoing advantages in the present invention, the slider is provided with a one piece, spring actuated locking element, which extends longitudinally of the slider, and lies relatively close to the body portion, so as to provide a relatively thin construction. The locking element being made in one piece it is relatively easy to assemble and economical to manufacture.

The foregoing objects and other features of the invention will be more clearly understood by referring to the following description and the accompanying drawing, in which:

Fig. 1 is a plan view of a slider embodying this invention and which is shown in operative connection with a separable fastener having a series of fastener elements;

Fig. 2 is a cross sectional view on line 2—2 of Fig. 1, looking in the direction of the arrows;

Fig. 3 is a front elevational view of the improved slider;

Fig. 4 is an isometric detailed view of the improved locking device, and the pull element for operating same.

Referring to Figs. 1 and 2 of the drawing the slider 10, embodying this invention, is illustrated in connection with a separable fastener 11, having a series of fastener elements 12 which are adapted to be interlocked with one another and spread apart by the slider 10. Referring to Fig. 3, the slider 10 comprises a pair of wings 13, which are adapted to slide over the fastener elements 12, and cause them to be interlocked by the curved flanges 14, which cooperate with the elements 12 in the usual manner when the slider is pulled in an upward direction as viewed in Fig. 1. The wings 13 are connected at the front end of the slider by a spreader element 15 which is interposed between the individual strings 16 of the fastener elements when the slider is assembled therewith. A one piece spring locking element 17 extends longitudinally of the slider 10, and one of its ends is secured to the front end 18 of the slider 10. The other end of the locking element 17 is

provided with an inwardly bent portion provided with a head 19, which extends through an opening 20 in the upper wing 13. The head 19 is provided with a projection 21 which is adapted to extend between the fastener elements 12 and thereby lock the slider 10 against unintentional movement in the rearward or opening direction. The locking head 19 is wider than the width of the opening 20 and is provided with shoulders 22 which overlap the longitudinal edges 23 of the opening 20. The head 19 is connected to the element 17 by a neck or reduced portion 24 having shoulders 25.

Referring to Fig. 4, the slider 10 and locking element 17 is operated by a pull element 26 having an opening 27 therein and through which the element 17 extends. The mid portion 28 of the element 17 is spaced from the upper wing 13 and the end of the pull 26 is adapted to slide in this space. In order to assemble the pull element 26 and the locking element 17 on the slider 10, the element 17 is extended through the opening 27 and the locking head 19 is extended through the opening 20 while the element 17 is arranged at an angle to the lengthwise direction of the slider. After the shoulders 22 pass through the opening 20, the element 17 is turned so that it is aligned longitudinally with the slider 10. The inwardly bent front end 29 of the locking element 17 is provided with a reduced portion 30 which fits in a groove 31 (Fig. 3) formed in the spreader 15 on the front of the slider 10. When the groove 31 is formed, the edges 32 thereof extend outwardly, and after the reduced portion 30 is positioned in the groove 31, the edges 32 of the groove are beaded over the portion 30 to retain the end of the element 17 in a fixed position. The shoulders 31' at the ends of the reduced portion 30 bear against the beaded over edges 32.

The front end of the element 17 being held in a fixed position the locking projection 21 is normally resiliently positioned between the fastener elements 12. The shoulders 25 are adapted to engage the top surface of the wing 13 to prevent the head 19 from being pushed down too far, and the shoulders 22 are adapted to engage the beveled edges 33 of the opening 20 to prevent the head 19 from being pulled through the opening. The edges 33 are beveled to provide a greater space for the head 19 without increasing the thickness of the slider to the end that more metal can be put in the head to increase its strength.

The locking projection 21 is provided with a beveled edge 34 which permits the projections 21 to slide over the elements when the pull 26 is

5 moved in a forward direction to move the slider and close the fastener. The rear portion of the locking element 17 is provided with an inclined portion 35 against which the end of the pull 26
10 may be wedged when it is moved in a rearward direction to separate the fastener elements 12. The locking projection 21 is moved upwardly out of engagement with the fastener elements 12 by such wedging movement and thereby permits the slider 10 to be operated.

15 While one embodiment of this invention has been described in detail, it will be understood that changes may be made therein, and it is desired to protect the invention to the extent permitted by the prior art and to the extent covered by the scope of the appended claims.

20 Having thus described my invention, what I claim and desire to protect by Letters Patent is:

25 1. A slider for a separable fastener comprising two wings and a spreader member interposed at their front ends, said wings and spreader being adapted to slide in contact with the fastener elements to engage and disengage same, a lock for said slider comprising a leaf spring element extending lengthwise of said wings and secured at one end to the front end of said slider, said spring having a mid portion which is spaced from the wing adjacent thereto and a rear end portion which is bent inwardly towards said wing, said inwardly bent portion having a locking head which is provided with a shoulder at the side edge thereof, said wing having an opening in its rear portion, said head and shoulder extending through said opening, and said shoulder overhanging the edge of said opening to prevent the removal of the locking head from said opening after the opposite end of said spring has been secured in place, said head having a projection thereon which is adapted to be resiliently held by the spring between the fastener elements to prevent the movement of the slider in the direction to disengage the fastener elements, and a pull member adapted to operate said slider and move said locking projection out of locking engagement with the fastener elements.

30 2. A slider for a separable fastener comprising two wings and a spreader member interposed at their front ends, said wings and spreader being adapted to slide in contact with the fastener elements to engage and disengage same, a lock for said slider comprising a leaf spring element extending lengthwise of said wings said spring having its front end notched out and bent over the front end of said wings, said notched out portion fitting into a groove in the front end of said slider

35 and secured therein by beading the edges of the groove over the notched out portion, said spring having a mid portion which is spaced from the wing adjacent thereto and a rear end portion which is bent inwardly towards said wing, said inwardly bent portion having a locking head which is provided with a shoulder at the side edge thereof, said wing having an opening in its rear portion, said head and shoulder extending through said opening and said shoulder overhanging the edge of said opening to prevent the removal of the locking head from said opening after the opposite end of said spring has been secured in place, said head having a projection thereon which is adapted to be resiliently held by the spring between the fastener elements to prevent the movement of the slider in the direction to disengage the fastener elements, and a pull member adapted to operate said slider and move said locking projection out of locking engagement with the fastener elements.

40 3. A slider for a separable fastener comprising two wings and a spreader member interposed at their front ends, said wings and spreader being adapted to slide in contact with the fastener elements to engage and disengage same, a lock for said slider comprising a leaf spring element extending lengthwise of said wings and secured at one end to the front end of said slider, said spring having a mid portion which is spaced from the wing adjacent thereto and a rear end portion which is bent inwardly towards said wing, said inwardly bent portion having a locking head which is provided with a shoulder at the side edge thereof, said wing having an opening in its rear portion, said head and shoulder extending through said opening and said shoulder overhanging the edge of said opening to prevent the removal of the locking head from said opening after the opposite end of said spring has been secured in place, said head having a projection thereon which is adapted to be resiliently held by the spring between the fastener elements to prevent the movement of the slider in the direction to disengage the fastener elements, the edge of said opening being beveled and the outer edge of said shoulder being adapted to abut against said beveled edge to permit said shoulder to recede outwardly beyond the inside surface of said wing and thereby provide space to accommodate more metal in said shoulder, and a pull member adapted to operate said slider and move said locking projection out of locking engagement with the fastener elements.
